UNITED STATES PATENT OFFICE

131,870

DESIGN FOR A PLAQUE

Robert A. Wright, Rye, N. Y.

Application January 24, 1942, Serial No. 105,405

Term of patent 7 years

To all whom it may concern:

Be it known that I, Robert A. Wright, a citizen of the United States, residing in Rye, county of Westchester, State of New York, have invented a new, original, and ornamental Design for a Plaque, of which the following is a specification, reference being had to the accompanying drawing, forming a part thereof.

The figure of the drawing is a plan view of a plaque showing my new design.

The plaque has no appreciable thickness and the back thereof is plain.

I claim:

The ornamental design for a plaque, as shown and described.

ROBERT A. WRIGHT.
